Jefferson Franklin Gentry

UNITED STATES PATENT OFFICE

JEFFERSON F. GENTRY, OF NASHVILLE, TENNESSEE

PERFORATING DEVICE

Application filed February 24, 1931. Serial No. 517,982.

This invention relates to a perforating device for platen presses and has for its primary object to provide, in a manner as hereinafter set forth, a device of such character by means of which paper stock may be perforated simultaneously with the printing thereof, thereby reducing the time and labor ordinarily necessary to print and perforate a supply of paper, and assuring uniformity 10 of the perforations with respect to the printing.

With the foregoing and other objects in view, the invention consists of the novel construction, combination and arrangement of parts as hereinafter more particularly described, and shown in the accompanying drawings, but it is to be understood that the description and drawings are to be considered as illustrative rather than limitative.

20 In the accompanying drawings in which like numerals are employed to designate like parts throughout the several views:

Figure 1 is a fragmentary plan showing a perforating device in accordance with this 25 invention.

Figure 2 is a transverse section through the device with the perforating die shown in elevation.

Figure 3 is an enlarged fragmentary section through the device showing the relative position of the parts just prior to the perforating operation.

Figure 4 is a view similar to Figure 3 showing the relative position of the parts during 35 the perforating operation.

Referring to the drawings in detail, the numerals 1 and 2 respectively indicate the platen and rocker of a press, the rocker 2 being adapted to carry the usual gripper bars, not 40 shown. Seated on the platen 1 is a mat indicated generally at 3 and including a rectangular frame 4 which is rigidly secured in any suitable manner to the platen 1. By way of example, a plurality of clamps 5 are illustrated 45 for securing the frame 4 in position on the platen.

Disposed within the confines of the frame 4 are a plurality of plates, in the present instance three in number and designated by the 50 numerals 6, 7 and 8. Interposed between

the plates 7 and 8 is a guide plate 9, the side edges of which are detachably connected with the opposing edges of the plates 7 and 8 by means of removable tongues 10 which slidably extend within corresponding grooves in the side edges of the plates 7, 8 and 9. Although but one guide plate 9 is shown, this number may be increased if desired by varying the number or size of the plates 6, 7 and 8. By varying the size of the latter plates, one or more of the guide plates may be located at any point desired longitudinally of the frame 4. Irrespective of the number of guide plates employed, all of the plates within the frame are secured together by means of tongues, such as 10 which slidably extend into corresponding grooves in the opposing edges of contacting plates. The plates thus connected together are vertically slidable within the frame 4 and are normally maintained in spaced relation to the platen 1 by means of a plurality of leaf springs 11, one of which is provided for each of the plates 6, 7 and 8 and is disposed within a groove, such as 12, formed in the lower face of the plates.

The guide plate 9 is formed in its lower face with a relatively wide groove 13 for the reception therein of a punch bar 14 during the printing and perforating operation. The punch bar 14 is seated directly on the platen 1 and is of a width corresponding to the width of the groove 13. Seated on the punch bar 14 and extending into the groove 13 are leaf springs 15 similar to the leaf springs 11. Projecting upwardly from the punch bar 14 is a centrally disposed row of punches 16 which slidably extend into corresponding openings 17 extending vertically through the guide plate 9 centrally with respect to the side edges of the latter.

Fixedly secured to the rocker 2 is a die member which consists of an elongated bar 18 of channeled construction formed in its upper face with an elongated trough 19, and formed in its bottom with a row of openings 20 corresponding to the openings 17 in the guide plate 9. Adjacent one end thereof, the guide plate 9 is provided on its upper face with a pair of guide lugs 21 for receiving

the bar 18 therebetween when the latter is lowered into operating position.

In the operation of the device, the printing is performed in the usual manner, during which operation the plates 6, 7, 8 and 9 are pressed into contact with the platen 1 against the tension of the springs 11 and 15. Coincidentally with the printing operation, the die bar 18 is lowered, and upon the downward movement of the plates 6, 7, 8 and 9, the punches 16 are extended entirely through the openings 17 and 20 whereby the paper, shown at 22, is perforated. Immediately upon the release of the plates 6, 7, 8 and 9 by the movement of the rocker 2, the plates are elevated to the positions shown in Figures 2 and 3 by the operation of the springs disposed beneath the plates. This movement of the plates automatically withdraws the punches 16 from their projecting positions through the openings 17 in order that the plates may present a smooth uninterrupted surface for receiving the next sheet of paper to be printed and perforated.

It is thought that the many advantages of a perforating device in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:—

1. In a perforating device for connection with the platen and rocker of a printing press, a punch bar adapted to be seated on the platen, a guide plate resiliently supported above the punch bar for supporting the stock to be perforated, said guide plate having a row of vertically disposed openings, a row of punches projecting upwardly from the punch bar into said openings, and a die bar adapted to be connected with the rocker for engagement with the stock supported on the guide plate to force the punches through the stock upon the operation of the rocker.

2. In a perforating device for connection with the platen and rocker of a printing press, a punch bar adapted to be seated on the platen, a guide plate resiliently supported above the punch bar for supporting the stock to be perforated, said guide plate having a row of vertically disposed openings, a row of punches projecting upwardly from the punch bar into said openings, and a die bar adapted to be connected with the rocker for engagement with the stock supported on the guide plate to force the punches through the stock upon the operation of the rocker, said die bar being of channelled construction and formed in its upper face with an elongated trough, said die bar further being formed in its lower face with a row of openings corre-

sponding to said openings in the guide plate.

3. In a perforating device for connection with the platen and rocker of a printing press, a punch bar adapted to be seated on the platen, a guide plate for supporting the stock to be perforated, said guide plate having its lower face formed with a groove corresponding in width to the punch bar and further having a row of vertically disposed openings, a pair of leaf springs seated on the punch bar and extending into said groove for resiliently supporting the guide plate in spaced relation to the punch bar, a row of punches projecting upwardly from the punch bar into said openings, and a die bar adapted to be connected with the rocker for engagement with the stock supported on the guide plate to force the punches through the stock upon the operation of the rocker.

4. In a perforating device for connection with the platen and rocker of a printing press, a frame secured to the platen, a pair of plates vertically movable within the frame, a guide plate interposed between said pair of plates, means for resiliently supporting said plates in spaced relation to the platen, a punch bar disposed beneath the guide plate, said guide plate having its lower face formed with a groove corresponding in width to the width of the punch bar and further having a plurality of vertically disposed openings, a plurality of punches projecting upwardly from the punch bar into said openings, and a die bar connected with the rocker for depressing the guide plate to force said punches through the openings therein and into the die bar upon the operation of the rocker.

5. In a perforating device for connection with the platen and rocker of a printing press, a frame seated on and connected with the platen, a pair of plates vertically movable within the frame, a guide plate interposed between and connected with said plates, each of said plates formed in its lower face with a groove, leaf springs projecting into said grooves for normally maintaining the plates in spaced relation to the platen, a punch bar seated on the platen beneath the guide plate, said guide plate having a row of vertically disposed openings, a row of punches projecting upwardly from the punch bar into said openings, a die bar rigidly connected with the rocker for depressing the guide plate to extend said punches therethrough and into the die bar upon the operation of the rocker, and a pair of guide lugs mounted on the upper face of the guide plate for receiving said die bar therebetween.

In testimony whereof, I affix my signature hereto.

JEFFERSON F. GENTRY.
